UNITED STATES PATENT OFFICE.

EMIL POUYAT, OF LIMOGES, FRANCE.

DESIGN FOR A DISH.

SPECIFICATION forming part of Design No. 19,744, dated April 1, 1890.

Application filed December 23, 1889. Serial No. 334,797. Term of patent 14 years. Registered in France April 15, 1889, No. 204.

To all whom it may concern:

Be it known that I, EMIL POUYAT, a citizen of France, residing at Limoges, in the Department of Haute-Vienne, France, have invented and produced a new and original Design for Dishes, of which the following is a specification, reference being had to the accompanying drawings, forming a part thereof.

Figure 1 is a profile view of a soup-tureen or covered dish. Fig. 2 is a face view of a cover. Fig. 3 is a face view of a platter or deep dish. Fig. 4 is the face view of a plate, these four views being deemed necessary to fully illustrate my design.

15 The leading feature of my design consists in the convex form of the soup-tureen or covered dish, with the peculiar ornamentation of the handles, which are in the form of a crosier.

The form of the soup-tureen or covered dish, 20 Fig. 1, is oval, and the cover sits on a rim within raised edges. On the body of the soup-tureen or covered dish are raised panels A A A A, giving a convex shape to the dish. The handles B B B represent crosiers with scroll-work of the time of Louis XV. The handle 25 of the cover, Fig. 2, is also formed by the same

scroll-work, with ornaments on each side, attached to which are the same crosier designs which extend down the surface of the cover.

The platters, Fig. 3, are oblong. The outside circumference conforms to the broken outline of the soup-tureen or covered dish. There are also four raised panels A A A A. The handles are of the same style as those of the soup-tureen or covered dish, excepting 35 that they are in relief. The ornamentation and scroll-work are also the same.

The plates, Fig. 4, are divided into six raised panels C C C C C C. The outside and inside circumference of the rim D F follow the out- 40 line of the panels.

What I claim is—

1. The design for dishes herein shown and described.
2. In the design for dishes herein shown 45 and described, the handles raised or in relief and made to represent a crosier ornamented with scroll-work of the time of Louis XV.

EMIL POUYAT.
